UNITED STATES PATENT OFFICE.

LEONARD F. FULLER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

RADIOTELEGRAPHY.

1,358,143.

Specification of Letters Patent.

Patented Nov. 9, 1920.

Application filed August 30, 1918. Serial No. 252,033.

To all whom it may concern:

Be it known that I, LEONARD F. FULLER, a citizen of the United States, and a resident of Palo Alto, county of Santa Clara, and 5 State of California, have invented certain new and useful Improvements in Radiotelegraphy, of which the following is a specification.

The invention relates to a transmission 10 system of radiotelegraphy and particularly continuous-oscillation radiotelegraphy, involving variations in antenna inductance.

In my copending application, Serial No. 192,209, filed in the United States Patent 15 Office on September 19, 1917, I have shown a radiotelegraphy transmission system, involving an antenna loading coil and a loop circuit inductively connected thereto, which loop is opened and closed to vary the induct- 20 ance of the antenna circuit for signaling purposes. The loop circuit was divided into a plurality of segments, preferably of equal length by radial conductors, connected at one end to the loop at equally spaced points and connected together at their other ends, 25 at the center of the circle of the loop. A switch was arranged in each segment of the loop and means were provided for opening or closing all of the switches substantially 30 simultaneously, but in practice I have found that all of the switches are not opened at the same time.

Each radial conductor formed a common 35 side to two adjacent sectors and consequently the mutual inductance between adjacent sectors was high. Since the switches do not all open at the same time, the switch which opens first, would, at the start of its opening, have to break the current circulating in the 40 loop and would have across its contacts, the voltage of its sector. If there were ten sectors, this voltage should be one-tenth of the total reactive drop of the current through the circular loop. During the period that the 45 switch opened, less and less current would flow through the key contacts and more and more of the loop current would be forced through the radials of the sector that was being opened, until finally, when the switch 50 was wide open, no current would flow through the switch contacts and the total remaining loop current would flow down one radial to the center and up the other, thus shunting by the open key. Due to this fact,

the flux through the area of the open sector 55 due to the current in the radials, causes a greater voltage across the switch contacts, than one-tenth of the total loop voltage, be- cause this flux is in phase with the flux of the main loading coil. The main loading 60 coil flux links all sectors equally and when the switches start to open, the flux density in all of the sectors is equal, but as one switch opens, the flux through the opening sector is increased, producing a greater volt- 65 age across the switch contacts.

For example, if the loop radial system shown in the application mentioned above had to open a circuit of one hundred kilo-volt-amperes, and there were ten sectors, ex- 70 periments have shown that that the first switch to open would have to open about seventeen kilo-volt-amperes, an increase of 70% over the normal ten kilo-volt-amperes, and that the last switch of the ten would be oper- 75 ating at about five kilo-volt-amperes. This reduces the efficiency of the former system, since it is necessary to employ more switches and sectors, than if an equal number of kilo-volt-amperes were opened by each switch. 80

This presents a deleterious feature which it is an object of the present invention to overcome.

Another object of the present invention is to provide means for emitting wave trains 85 at a definite group frequency from an arc transmitting station.

The invention possesses other advanta- 90 geous features, some of which, with the fore- going, will be set forth at length in the fol- lowing description where I shall outline in full, that form of the invention which I have selected for illustration in the drawings accom- 95 panying and forming part of the pres- ent specification. In said drawings I have shown one specific form of the system of my invention, but it is to be understood that I do not limit myself to such form, since the invention, as expressed in the claims, may be embodied in a plurality of forms. 100

Referring to said drawings:

Figure 1 is a diagrammatic representation of a radiotelegraphy transmission system embodying my invention.

Fig. 2 is a diagrammatic representation of 105 the loop circuit of my invention.

The ordinary continuous oscillation trans- mission system may be represented by an arc

- 2 supplied with current from the generator 3. One side of the arc is grounded and the other side is connected to the antenna 4, through the variable inductance or loading coil 5.
- 5 Arranged in inductive relation with the loading coil 5 and preferably directly below the lower turn thereof, are a plurality of separate isolated sectors 6, the outer or arc-shaped conductors 7 of each sector lying in 10 a circle, preferably of substantially the same diameter as the loading coil. The radial conductors 8 of the sectors are spaced from each other circumferentially, so that the mutual inductance between adjacent sectors is 15 low, thereby obviating the difficulties of the former system, and the greater the spacing between the radial conductors 8, the less will be the mutual inductance and the greater will be the efficiency of the system.
- 20 Arranged in each sector and preferably in the arc shaped conductor 7 of each sector, is a switch or relay 9, the relays being arranged so that they may be operated substantially simultaneously. The solenoids 12 of the 25 relays are connected in series in the local circuit with the key 13.

In the present construction, with low mutual inductance between the sectors, it is possible to load each relay to its full load 30 value, since regardless of the sequence of the opening of the sectors, each relay will take its full load and no more, thereby reducing the number of relays from those required by the former system.

35 This system also lends itself advantageously to the emission of a tone frequency from an arc transmitting station. When it is desirable to produce a tone frequency, for example a five hundred cycle note, I connect 40 choppers or motor operated commutating devices 14 around each pair of relay contacts or in series with each pair of relay contacts, as desired. These choppers 14 must operate together and it is therefore desirable that 45 they be all arranged on the same shaft and operated together so that they all make and break contact at the same time.

I claim:

- 50 1. A radiotelegraphy transmission system including an antenna circuit, a loading coil in said circuit, a plurality of isolated sector circuits inductively connected to said loading coil and means for opening and closing the sector circuits.
- 55 2. A radiotelegraphy transmission system including an antenna circuit, a loading coil in said circuit, a plurality of isolated sector circuits inductively connected to said loading coil, a switch in each sector circuit and means 60 for operating said switches.

65 3. A radiotelegraphy transmission system including an antenna circuit, a loading coil

in said circuit, a plurality of isolated circuits arranged in the same inductive relation to said loading coil whereby a relatively small 65 current is induced in each isolated circuit and means for opening and closing said circuits.

4. A radiotelegraphy transmission system including an antenna circuit, a loading coil 70 in said circuit, a plurality of spaced conductors arranged adjacent to said coil and concentric to the axis thereof, conductors arranged within said concentric conductors and forming with the concentric conductors 75 a plurality of isolated circuits and means for opening and closing said circuits.

5. A radiotelegraphy transmission system including an antenna circuit, a loading coil in said circuit, a plurality of spaced conductors arranged adjacent to said coil and concentric to the axis thereof, conductors connected to the ends of said spaced conductors and extending toward said axis and forming 80 circuits with said spaced conductors and means for opening and closing said circuits.

6. A radiotelegraphy transmission system including an antenna circuit, a loading coil in said circuit, a plurality of sector circuits having low mutual inductance, inductively 90 connected to said loading coil and means for opening and closing the sector circuits.

7. A radiotelegraphy transmission system including an antenna circuit, a loading coil in said circuit, a plurality of sector circuits 95 inductively connected to said loading coil, means for opening and closing the sector circuits and means for interrupting the sector circuits at a tone frequency.

8. A radiotelegraphy transmission system 100 including an antenna circuit, a loading coil in said circuit, a plurality of isolated circuits arranged in the same inductive relation to said loading coil, means for opening the isolated circuits and means for regularly closing 105 and opening the isolated circuits at a tone frequency.

9. A radiotelegraphy transmission system including an antenna circuit, a loading coil in said circuit, a plurality of isolated sector 110 circuits inductively connected to said loading coil, a switch in each sector circuit and a chopper connected across each switch.

10. A radiotelegraphy transmission system, including an antenna circuit, a loading 115 coil in said circuit, a plurality of circuits arranged in the same inductive relation to said loading coil and means for opening and closing said last named circuits at a tone frequency.

In testimony whereof, I have hereunto set my hand at Palo Alto, California, this 21st day of August, 1918.

LEONARD F. FULLER.
